UNITED STATES PATENT OFFICE.

JOHN KENNEDY, OF MONTREAL, QUEBEC, CANADA.

DREDGING AND EXCAVATING MACHINE.

No. 851,093.

Specification of Letters Patent.

Patented April 23, 1907.

Application filed October 18, 1906. Serial No. 339,527.

To all whom it may concern:

Be it known that I, JOHN KENNEDY, of the city of Montreal, Province of Quebec, Canada, have invented certain new and useful

5 Improvements in Dredging and Excavating Machines; and I do hereby declare that the following is a full, clear, and exact description of the same.

My invention relates particularly to the 10 teeth of the buckets of dredging and excavating machines, and it has for its object to increase the utility of these devices and render them more easily and cheaply renewable.

The invention may be said briefly to consist of a tooth comprising a carrying member and a changeable point, one of such parts having a pair of tapered plate-like flanges overlapping the other part and fitting into recesses therein the point and carrying member 15 thereby each presenting a portion within the length of the overlapping devices and equal in depth at that point to the greatest cross-section of the flanges and the portion of the said carrying member they overlap. The 20 point is secured in place and the slack between it and the carrying member taken up by a tapered key driven transversely through registering portions of the said point and carrying member.

25 For full comprehension, however, of my invention reference must be had to the accompanying drawings, forming a part of this specification, in which similar reference characters indicate the same parts and wherein:

30 Figure 1 is a side elevation of a portion of a dredging or excavating bucket with my invention applied thereto; Figs. 2 and 3 are a side elevation and a plan view, respectively, of my improved tooth; Fig. 4 is a detail view 35 of the shank alone; Fig. 5 is a like view of the changeable point; Figs. 6, 7, 8, and 9 are transverse sectional views taken on the respective lines A A, B B, D D, and E E, Fig. 2; and Fig. 10 is a longitudinal sectional view 40 taken on line C C Fig. 2.

The changeable point consists of a wedge shaped member cored out to present a pair of wedge shaped recesses *c* between flanges *e* and divided by a web *d*, and each flange *e* is 45 reduced abruptly in width, as at *e*, about midway of its length, and tapered from such point to its rear end where its corners are

rounded as at *f*, the web preferably projecting slightly beyond the ends of the said flanges. The part upon which this changeable point is carried presents a pair of wedge-shaped members *g* separated by a space *h* into which the web *d* fits loosely and the converging sides, or top and bottom, of these members have tapered recesses *i* adapted to 55 receive the tapered portions of the flanges *e* of the point, while the said members *g* fit into the wedge shaped recesses *c*. A tapered hole *k* is made through the members *g* and a hole *m* in the web coincides therewith when the 60 point is in place, while a tapered key or cotter *n* prevents longitudinal displacement of the point and while being driven home draws the point tightly upon its carrying member a 65 perfect splice being effected.

70 By means of my improved construction of the changeable point and its carrying member, both tooth and carrying member have their full depth throughout the whole or greater part of the length of the splice; the 75 tapered recesses in the top and bottom of the carrying member and the tapered top and bottom flanges of the point, fitting into these recesses, cause such point and carrying member to be rigidly wedged together thereby 80 preventing lateral or horizontal movement; and the wedge shaped members fitting into the wedge-shaped recesses between the flanges of the point cause the latter and its carrying member to be wedged together 85 against displacement up and down, and, consequently, at right angles to the first mentioned wedging action; while the tapered key or cotter enables the slack between the point and its carrying member to be taken up.

90 My improved changeable point can, when its edge is worn and the flatness of its underside disturbed, be reversed and the top turned to the bottom, and to enable this to be done the tapered hole is placed in the middle and 95 the apex is kept comparatively thick to within a short distance of the edge (as at *u*) and the top side is inclined sharply to the apex (as at *v*), while the bottom flat side is extended to the apex. Heretofore when the 100 tooth was worn to the dotted line *w* it had to be removed, heated, and drawn before it could be again set in place and used. When my improved changeable point is worn the

tapered key or cotter is driven out, and the point knocked off and reversed and again wedged upon its carrying member, the point *u* at which the greater thickness terminates 5 presenting an even edge which constitutes the apex of the tooth. It will be noted that this change is effected without removing the carrying member.

The carrying member I have illustrated is 10 in the form of a shank *s* of the type bolted to the exterior of the bottom of a dredging bucket *t*. This particular carrying member is shown as an instance only as the invention can be equally well applied to the shanks secured upon the inside of the bucket bottom, or the member can, in the case of elevator dredges and other types of dredges and excavators be cast solid with the lip of the bucket, in fact the invention is applicable wherever 15 dredging or excavating teeth are used.

If desired the recesses in the converging sides of the point and carrying member can be varied in form without departing from the spirit of my invention.

25 What I claim is as follows:—

1. A tooth for dredging and excavating machines and the like comprising a carrying member and a changeable point, one of such parts having a pair of plate-like flanges of less 30 width than and overlapping the other part, the said other part having recesses into which the said flanges fit.

2. In a tooth for dredging and excavating machines, the combination with a carrier 35 presenting a pair of separated wedge shaped members, of a changeable point presenting a pair of wedge shaped recesses divided by a web, means securing the point upon the carrier with the members wedged in the recesses and the web between the said members and means distinct from the web for preventing displacement of the point in a direction transversely to the tooth.

3. A tooth for dredging and excavating 45 machines, and the like, comprising a part consisting of a carrying member and a second part consisting of a changeable point, one of the said parts having tapered plate-like flanges fitting into corresponding recesses 50 in the other part.

4. A tooth for dredging and excavating machines, and the like, comprising a part consisting of a carrying member and a second part consisting of a changeable point, one of 55 the said parts having plate-like flanges fitting into recesses in the other part; the plate-like devices being tied together by a web and the said other part having a slot for accommodating the web.

5. A tooth for dredging and excavating machines, and the like, comprising a part consisting of a carrying member and a second part consisting of a changeable point,

one of the said parts having plate-like flanges fitting into recesses in the other part; and 55 means whereby the slack between the said parts is taken up.

6. In a tooth for dredging and excavating machines, the combination with a wedge shaped carrying member with recesses in 70 their converging faces, such recesses being tapered in their longitudinal direction, of a changeable point presenting a wedge shaped recess adapted to receive the carrying member, and tapered flanges adapted to fit into 75 the tapered recesses of such member, and means securing the point in wedging relation with the carrying member.

7. In a tooth for dredging and excavating machines, the combination with a wedge shaped carrying member, of a changeable point presenting a wedge shaped recess adapted to receive the carrying member, a 80 tapered key or cotter securing the point in wedging relation with the carrying member 85 and adapted to take up the slack between the said parts, and means preventing lateral displacement of the said point.

8. A tooth for dredging and excavating machines, and the like, comprising a trans- 90 versely perforated tapered carrying member and a changeable point recessed to fit upon the said tapered carrying member and presenting a part with a perforation adapted when the parts are in operative position to 95 register with the perforation in the carrying member, and a tapered pin engaging in the registering perforations for securing the point in place and whereby the slack between the said parts is taken up.

9. In a tooth for dredging and excavating machines, the combination with a carrier 100 presenting a pair of separated wedge shaped members with recesses in their converging faces such recesses being tapered in their 105 longitudinal direction, of a changeable point presenting a pair of wedge shaped recesses divided by a web and having tapered flanges adapted to fit into the tapered recesses of such member, and a tapered key or cotter 110 securing the point upon the carrier with the members wedged in the wedge shaped recesses the tapered flanges in the tapered recesses and the web between the said members, such key or cotter being adapted to 115 take up the slack between the said parts.

10. In a tooth for dredging and excavating machines, the combination with a carrying member, of a reversible changeable point.

11. In a tooth for dredging and excavating machines, the combination with a carrying member, of a reversible changeable converging point with one side flat and its other side inclined to its apex in two angular planes.

12. A tooth for the purpose set forth, comprising a carrier presenting wedge shaped

members *g g*, space *h*, recesses *i* tapered in their longitudinal direction, and holes *k*; and a changeable point presenting a pair of wedge shaped recesses *c*, web *d* having hole 5 *m*, and tapered flanges *e*, reduced abruptly in width as at *r*; and a tapered key or cotter *n*.

In testimony whereof, I have signed my

name to this specification, in the presence of two subscribing witnesses:

JOHN KENNEDY.
